(57) **CLAIM**

The ornamental design for a neck pillow, as shown and described.

DESCRIPTION

FIG. 1 is a three-quarter view of the neck pillow showing my new design;

FIG. 2 is a front view;

FIG. 3 is a back view;

FIG. 4 is a left side view;

FIG. 5 is a right side view;

FIG. 6 is a top view; and,

FIG. 7 is a bottom view.

The dash-dash lines on top of the neck pillow represent stitching and form part of the claimed design. The dot-dot-dash lines on the bottom of the neck pillow are for illustrative purposes only and form no part of the claimed design.
